(57) **CLAIM**

The ornamental design for an infusion beverage apparatus, as shown and described.

DESCRIPTION

FIG. 1 is a perspective view of the infusion beverage apparatus according to my new design;

FIG. 2 is a front view of the infusion beverage apparatus of FIG. 1;

FIG. 3 is a right side view of the infusion beverage apparatus of FIG. 1, the left side view being a mirror image thereof;

FIG. 4 is a rear view of the infusion beverage apparatus of FIG. 1;

FIG. 5 is a top view of the infusion beverage apparatus of FIG. 1;

FIG. 6 is a bottom view of the infusion beverage apparatus of FIG. 1; and,

FIG. 7 is a cross sectional view of the infusion beverage apparatus of FIG. 1 taken at Line 7-7 of FIG. 2.

Components shown in broken lines are for environment only and form no part of the claimed design.
